G. W. BENAGE.

CALF WEANER.

APPLICATION FILED OCT. 29, 1914.

1,144,020.

Patented June 22, 1915.

UNITED STATES PATENT OFFICE.

GEORGE W. BENAGE, OF JUDA, WISCONSIN.

CAFE-WEANER.

1,144,020.

Specification of Letters Patent. Patented June 22, 1915.

Application filed October 29, 1914. Serial No. 869,287.

To all whom it may concern:

Be it known that I, GEORGE W. BENAGE, a citizen of the United States, residing at Juda, in the county of Green and State of Wisconsin, have invented certain new and useful Improvements in Calf-Weaners, of which the following is a specification.

This invention relates to a calf weaner and is an improvement over the construction shown in my prior Patents Numbers 1,077,585 and 1,051,064.

A particular object of this invention is to provide a device of the character described which is so constructed that it may be securely held in place and which will not move freely with a pivotal action when in place.

Another object of the invention is to so construct the device that the prongs which form part of the same may be screwed into threaded openings and thus removably held in place.

This invention is illustrated in the accompanying drawings wherein;

Figure 1 is a view showing the device in front elevation. Fig. 2 is a view showing the device in side elevation. Fig. 3 is a vertical sectional view taken along the line 3-3 of Fig. 1. Fig. 4 is an enlarged sectional view of one portion of the device.

The body portion of this device is in the form of a plate 10, which has its central portion reduced, thus forming a neck as shown in Fig. 1, the plate being bent transversely so that the end portions 11 and 12 will extend rearwardly, thus permitting the attachment to fit against the calf's nose with the lower portion 12 of the plate extending in front of the nose and the upper portion 11 resting above the nose.

A bridge or clamp 13 is formed from a strip of resilient metal which has its end portions bent to form the arms 14. The end portions of these arms are bent to form fingers 15 which extend in spaced relation to the arms 14 and are each provided with a threaded opening 16 positioned in alignment with a larger unthreaded opening 17 formed in its arm 14 as shown in Fig. 4. Stems 18 which are threaded, pass through the openings 16 and 17 and are provided at their inner ends with heads 19, and at their outer ends with flattened turning elements 20. Jackets 21 are provided for the heads 19 so that the stems may be turned without injury to the calf.

Reinforcing strips 22 and 23 are positioned adjacent the ends of the plate or body portion and are provided with threaded openings, thus permitting the prongs 24 and 25 to be easily connected with the plate. By this arrangement it is not necessary to rivet the prongs to the plates and therefore if desired the prongs may be removed and new ones put in place. It should be noted that the prongs 24 are straight throughout their length, whereas the prongs 25 have their free end portions curved downwardly as shown in Figs. 2 and 3, thus causing this device to be more effective in use.

When this device is in use the plate is fitted against the calf's nose with the heads 19 of the stems fitting into the nostrils. The stems can now be turned a sufficient amount to move the heads into the nostrils far enough to prevent any danger of the device slipping out of place. By having the stems mounted as shown in Fig. 4 the device will not interfere with the free breathing of the calf, since the stems can slip through the openings 17. This construction will also permit the device to be easily put in place or removed, since when it is desired to remove the device or to put it in place the stems can be drawn outwardly through the openings 17, this making it unnecessary to rotate the stems a very great amount. I have therefore provided a device of the character described which can be easily and quickly put into place and removed, and which will be very securely held in place without danger of interfering with the calf's breathing or of injuring the tender membranes within the calf's nostrils.

This device will operate very efficiently since when a calf is feeding it has a natural tendency to butt the cow with its nose. This will cause the prongs 24 to stick into the cow and she will then make the calf step to one side. The curved prongs 25 will also have a tendency to prick the cow's bag or teat thus causing the cow to push the calf to one side. It will therefore be seen that this device will operate very efficiently.

What is claimed is:

1. A device of the character described comprising a body portion, a yoke carried by said body portion, said yoke being formed from a resilient strip having its end portions bent to form arms, the free end portions of said arms being bent to form fingers extending inwardly in spaced relation to

the arms, said fingers being provided with threaded openings formed in alinement with unthreaded openings in said arms, and threaded stems passing through the alined openings of said arms and fingers.

2. A device of the character described comprising a body portion, a yoke carried by said body portion, said yoke including resilient arms having their end portions terminating in fingers extending in spaced relation to the arms and provided with threaded openings formed in alinement with unthreaded openings formed in said arms, and securing stems passing through the alined openings of said arms and fingers, whereby said stems will constitute means for permitting the fingers to be moved with relation to said arms.

3. A device of the character described comprising a body portion, a yoke carried by said body portion, said yoke being formed from a strip of resilient material and having its end portions bent to form arms terminating in fingers extending in spaced relation to the arms, and securing stems adjustably connected with said fingers and slidably engaging said arms to permit said fingers and stems to be moved simultaneously with respect to said arms.

In testimony whereof I affix my signature 30
in presence of two witnesses.

GEORGE W. BENAGE.
